Primary Examiner—Sandra L. Morris[57] **CLAIM**

The ornamental design for a game board, as shown.

DESCRIPTION

The sole FIGURE is a top plan view of a game board, showing my new design.

1 Claim, 1 Drawing Sheet**NEIGHBORS**# NEIGHBORS

Collect any money in "POTLUCK" and roll die to determine the following:

1. Exchange property (not money) with homeowner noted on die.
2. Clean "Garbage Pile" - pick up all cards on "Garbage Pile".
3. Sleep in unoccupied - roll die and visit neighbor.
4. Pay "Potluck" half your money for back taxes.
5. Clean "Lose" - collect 3 SLOB Cards face up on the bottom of the Garbage Pile.
6. Pick Slob. Collect \$100 by lottery.
